UNITED STATES PATENT OFFICE.

WILLIAM P. THOMPSON, OF LIVERPOOL, ENGLAND.

MARINE PROPULSION.

No. 904,464.

Specification of Letters Patent.

Patented Nov. 17, 1908.

Original application filed November 20, 1903, Serial No. 181,999. Divided and this application filed July 16, 1907.

Serial No. 384,120.

To all whom it may concern:

Be it known that I, WILLIAM P. THOMPSON, a subject of the King of Great Britain, residing at Liverpool, England, have invented certain new and useful Improvements in Marine Propulsion, of which the following is a description, reference being had to the accompanying drawing and to the letters and figures of reference marked thereon.

0 This case is a division of case Serial No. 181,999, filed Nov. 20, 1903.

This invention relates to marine propulsion, and has for its principal object to provide a novel form of vessel supporting means 15 by which the hull of the vessel is raised out of the water a distance proportioned to the rate of travel, for the purpose of reducing the resistance to the travel of the vessel.

A further object of the invention is to provide a vessel with a number of supporting fins that present inclined faces, which as the speed of the vessel increases, raise the hull, the fins being disposed at an angle or angles to the horizontal both transversely and in the 25 direction of their lengths, so that as the speed increases and the hull is raised there will be less and less of the area of the fins submerged.

With these and other objects in view, as 30 will more fully hereinafter appear, the invention consists in certain novel features of construction and arrangement of parts, hereinafter fully described, illustrated in the accompanying drawings, and particularly 35 pointed out in the appended claims, it being understood that various changes in the form, proportions, size and minor details of the structure may be made without departing from the spirit or sacrificing any of the advantages of the invention.

In the accompanying drawings: Figure 1 is a side elevation of a vessel having fins constructed and arranged in accordance with the invention, the fins being shown in section and the struts or braces omitted. Fig. 2 is an end elevation of the same, only one 45 set of fins and struts being shown in place.

Similar letters of reference are employed to indicate corresponding parts throughout 50 the several figures of the drawings.

The hull A is shown as provided with a keel that is formed of a plurality of sections B that are spaced from each other and gradually incline or curve downward and rearward from their front ends, or the keel may

be continuous as is usual in vessel construction.

Projecting from the vessel, preferably from the sides of the keel, are fins C of which there may be any desired number, these fins 60 being in the form of long, thin, sharp-edged blades, which considered transversely, are arranged at a slight angle to the horizontal, their forward sharpened edges being higher than their after edges, thus forming what 65 may be termed aquaplanes which cause the vessel to rise up on the surface of the water and reduce the draft. The outer ends of said fins are preferably supported by struts D which are secured to the sides of the vessel. For propelling purposes a lever or frame E is pivoted on a power shaft F and is provided at its free end with a shaft H on which is mounted a paddle wheel I of any 70 preferred construction, the paddle wheel 75 being driven from the shaft by means of a suitable belt G. The shaft H is guided in an arcuate slot R and may be adjusted by means of a ratchet or gear wheel J working in a suitable rack carried by the lever or 80 frame E, this mechanism being for the purpose of adjusting the height of the paddle wheel in accordance with the draft. In addition to the paddle wheel it is preferred to employ a screw propeller T which may be 85 driven in any suitable manner.

The fins are preferably disposed in a number of sets, all of those of the same set being preferably in the same horizontal plane, as will be evident on reference to Fig. 1, and as 90 the speed of the vessel increases, the hull will ride up on these fins and the fins will emerge from the water, the number of fins which remain submerged being dependent to a considerable extent on the speed at 95 which the vessel is traveling. This feature is taken advantage of in the present case by disposing the fins at an angle to the horizontal in the direction of their lengths, that is to say, the fins are angularly disposed in a 100 direction transverse of the vessel, so that even if only one set of fins is used, the submerged fin surface will grow gradually less and less as the vessel rises.

When the vessel is at rest, the entire surfaces of all of the fins will be submerged, but as the speed increases the tips of the fins will gradually show above the surface of the water and less and less of the fin surface will be submerged as the speed increases. 110

I claim:—

1. In a vessel, a series of fins having their inner ends directly connected to the vessel and extending out laterally beyond the gunwale, said fins being oblique with the horizon in the lateral as well as in the longitudinal.

2. In a vessel, supporting fins in the form of long, thin, narrow blades, disposed obliquely transversely of the vessel, the innermost ends of the fins being connected to the vessel and their outermost ends being extended beyond the gunwale, each fin being disposed at an angle in the direction of its width, the forward edge being in a plane above the after edge.

3. In a vessel, a series of fins connected directly to the keel and extending outward beyond the gunwale, said fins being disposed obliquely to the horizontal, both beamwise and fore and aft of the vessel.

4. A vessel having supporting fins in the form of long thin narrow blades having their inner ends connected to the vessel extending out beyond the gunwale on each side transversely and with their surfaces oblique to the horizon both in a fore and aft direction, and transversely.

5. In a vessel, the combination of one or

more series of long narrow fins having their inner ends connected to the vessel, said fins having surfaces oblique to the horizon transversely to the vessel as well as longitudinally with it, and the outer ends of said fins being connected rigidly to the vessel by struts approximately at right angles to the surface of the fins.

6. In a vessel, the combination of a series of long narrow fins C largely beneath the vessel, but extending out laterally beyond the vessel with a surface oblique to the horizon both in their length and in their breadth, and oblique struts D connecting their ends rigidly with the vessel above the water line.

7. The combination of a vessel, a series of transverse long narrow fins or aquaplanes, projecting beyond the gunwale and a series of oblique struts projecting outward from the side of the vessel above the center line, and connected to the outer ends of the said fins, whereby these side plates act somewhat as an outrigger in steadyng the vessels.

In testimony whereof I affix my signature, in presence of two witnesses.

WM. P. THOMPSON.
